Peter Stephenson of Boston Mass
Letters Patent No 495 Dated Sept 7th 1852.

Des. 495

The schedule referred to in these Letters Patent and making part of the same

To all Persons to whom these Presents shall come;

Be it known that Peter Stephenson of Boston in the
County of Suffolk and State of Massachusetts have produced a new and original
design for a medallion of Winfield Scott and I hereby declare that the said new
design is fully described and represented in the following specification and
accompanying drawings to which reference is hereinafter made.

The figures of the accompanying drawings represent
my new design. Fig 1 is a front elevation of the same. Fig 2 is a section taken
in the plane of the line A. B fig 1.

The head a. a, is cast in alto relief; the shoulders
covered with a military coat ff on the oval panel b b which is set in a frame
e c ornamented with the bead moulding d d and twisted moulding e e.

Having thus described my new design I shall state
my claim as follows.

What I claim is the design of a medallion of Win-
field Scott as represented in the drawings above referred to.
